UNITED STATES PATENT OFFICE.

CLARENCE R. WELCH, OF DENVER, COLORADO.

AUTOMOBILE-LOCK.

1,359,213.

Specification of Letters Patent. Patented Nov. 16, 1920.

Application filed March 4, 1919. Serial No. 280,551.

To all whom it may concern:

Be it known that I, CLARENCE R. WELCH, a citizen of the United States, residing at the city and county of Denver and State of Colorado, have invented certain new and useful Improvements in Automobile-Locks; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in automobile locks, my object being to provide a device of simple and economical construction which may be applied to the casing through which the steering post passes, and so constructed and arranged as to be brought into engagement with the steering post when it is desired to lock the machine against theft.

The device consists of two hingedly connected members arranged to surround the casing of the steering post, each member or jaw having a projection which extends inwardly through the casing and whose inner extremity is adapted to enter a perforation in the steering post when it is desired to lock the latter against rotary movement. The extremities of the two hinged members are reinforced, and in one of them is mounted the rotary barrel of a lock of ordinary construction, the said barrel having a projection adapted to engage a cavity formed in the adjacent reinforced part of the other member. By properly manipulating the barrel by the use of a key, the barrel projection may be made to engage the adjacent reinforced part in locking or released relation, as may be desired. As soon as the two members are unlocked by the proper manipulation of the lock barrel, a couple of springs are so arranged as to automatically separate the two members sufficiently to disengage the inner ends of their projections from the perforations in the steering post, thus allowing the latter to operate in the usual way.

Having briefly outlined my improvement, I will proceed to describe the same in detail,

reference being made to the accompanying drawing, in which is illustrated an embodiment thereof. In this drawing:

Fig. 1 is a fragmentary view of the body of an automobile, showing the steering post construction with my improved lock applied.

Fig. 2 is a cross section taken through the lock, the steering post and its casing, the device being shown in the locked position and on a larger scale.

Fig. 3 is a similar view, showing the device in the unlocked position.

Fig. 4 is a detail view of the lock shown in side elevation, being a view looking in the direction of arrows 4, Fig. 2.

The same reference characters indicate the same parts in all the views.

Let the numeral 5 designate the body of an automobile, 6 the steering post, and 7 the cylindrical casing surrounding the post, the post being manipulated by a wheel 8 in the ordinary manner.

Surrounding the casing 7 of the steering post, and preferably a short distance below the steering wheel, is located my improved lock, which I will designate in its entirety by the numeral 9. This lock consists of two members 10 and 12 which are curved interiorly to correspond with the curvature of the casing 7, and are connected by a hinge pin 32. Each jaw is provided with an interiorly projecting part 13, adapted to pass through a perforation formed in the casing 7. The inner extremity of each of these projections as illustrated in the drawing is reduced in size, as shown at 14, and is arranged to enter a perforation 15 in the steering post. As shown in the drawing, the two projections 13 are arranged in opposing relation and when the members 10 and 12 are closed, they engage both the casing and the steering post. The extremity of the member 10, remote from the hinge pin is reinforced as shown at 16, and in it is rotatably mounted a lock barrel, 17, of ordinary construction and arranged to coöperate with spring-actuated pins, some of which project into the barrel while others are located in the reinforcement 16. This mechanism is of ordinary construction.

When a key, 18, is inserted in the key-

hole of the reinforcement 16, the pins are so adjusted as to permit the rotation of the bar, 5 rel, which is provided at its extremity opposite the keyhole with a projection 19, carrying a cross piece, 20. The part 19 is adapted to enter an opening 21, formed in the reinforcement 22 of the member 12 and communicating with a larger recess 23, which extends on both sides of the perforation 21 and 10 is adapted to receive the cross piece 20 when the barrel is adjusted to lock the two members to cause their projections to engage the steering post in locking relation.

As shown in the drawing, the reinforcement 15 16 is provided with a pin 24, which is arranged to pass through an opening 25 formed in a projection 26 formed on the reinforcement 22 of the member 12. This pin 24 is provided with a head or enlargement 27, which is too large to pass through the perforation 25, and consequently will prevent the two members of the lock from opening far enough to become released from the casing of the steering post. Each of the 20 members 10 and 12 is provided with a recess 28, in which is seated a spiral spring 29, one extremity of which bears against the steering post casing. When the device is in the locked position, the springs 28 are under 25 tension, and as soon as the two members are unlocked by the proper manipulation of the lock barrel, the tension of the springs serves to automatically separate the members sufficiently to disengage their projections from the steering post, thus unlocking the latter and allowing it to turn freely or in the usual manner.

From the foregoing description, the use 40 and operation of my improved automobile lock will be readily understood.

In order to apply the lock, it will only be necessary to form openings in two opposite sides of the steering post casing and corresponding perforations in the steering post. 45 The openings in the steering post casing will be somewhat larger than the projections 13 which pass therethrough in order to compensate for the movement of the members from the axis of the hinge pin as a center 50 when the lock is thrown to the open position as illustrated in Fig. 3.

It will be understood that as the projections 13 are always in engagement with the openings in the casing of the steering post, 55 the device is securely connected with the said casing against removal, the pin 24 serving to prevent the members from sepa-

rating far enough to become disengaged from the said casing.

I claim:

1. An automobile lock, comprising in combination with the steering post and casing, two movably connected members applied to the steering post casing, the said device having a projection adapted to enter openings formed in the casing and post, means for releasably securing the two members in locking relation with the steering post and means for limiting the separation of said member when released, comprising 70 an apertured part on one member and a headed pin on the other member projecting through the aperture.

2. An automobile lock, comprising in combination with the steering post and its casing, two movably connected members applied to the steering post casing, the said device having a projection adapted to enter openings formed in the casing and post, means for releasably securing the two members in locking relation with the post, and means for automatically actuating a part of the device to disengage the projection from the steering post comprising a spring seated in the device and engaging the said 85 casing.

3. In an automobile lock, the combination with the steering post and casing having registering perforations, of two members movably connected, one of the members having a projection adapted to engage the openings in the steering post and casing when the device is in locking position, a lock for connecting the free extremities of the said members, and means for automatically separating the two members when the lock is released comprising a spring positioned between and engaging one of the members and said casing.

4. An automobile lock, comprising in combination with the steering post and its casing, two hingedly connected members having projections adapted to enter openings formed in said casing and post, releasable means for securing the two members in locking relation with the steering post, and means for automatically separating the two members when the lock is released, the said last named means including springs seated in the respective members and bearing 110 against the said casing.

In testimony whereof I affix my signature.

CLARENCE R. WELCH.
